(57) **CLAIM**

The ornamental design for a slap-on type earphone storage case, as shown and described.

DESCRIPTION

FIG. 1 is a perspective view, as seen from above, of a first embodiment of the slap-on type earphone storage case;

FIG. 2 is a perspective view, as seen from below, of the slap-on type earphone storage case of FIG. 1;

FIG. 3 is a top elevation of the slap-on type earphone storage case of FIG. 1;

FIG. 4 is a bottom elevation of the slap-on type earphone storage case of FIG. 1;

FIG. 5 is a front elevation of the slap-on type earphone storage case of FIG. 1;

FIG. 6 is a back elevation of the slap-on type earphone storage case of FIG. 1;

FIG. 7 is a left side elevation of the slap-on type earphone storage case of FIG. 1;

FIG. 8 is a right side elevation of the slap-on type earphone storage case of FIG. 1;

FIG. 9 is a perspective view, as seen from above, of the slap-on type earphone storage case of FIG. 1 in use on a mobile phone;

FIG. 10 is a perspective view, as seen from above, of a second embodiment of the slap-on type earphone storage case;

FIG. 11 is a perspective view, as seen from below, of the slap-on type earphone storage case of FIG. 10;

FIG. 12 is a top elevation of the slap-on type earphone storage case of FIG. 10;

FIG. 13 is a bottom elevation of the slap-on type earphone storage case of FIG. 10;

FIG. 14 is a front elevation of the slap-on type earphone storage case of FIG. 10;

FIG. 15 is a back elevation of the slap-on type earphone storage case of FIG. 10;

FIG. 16 is a left side elevation of the slap-on type earphone storage case of FIG. 10, an opposing elevation of the slap-on type earphone storage case being a mirror image thereof; and, FIG. 17 is a perspective view, as seen from above, of the slap-on type earphone storage case of FIG. 10 in use on a mobile phone.

The broken lines shown in FIGS. 9 and 17 are included for the purpose of illustrating the claimed design in use on a phone. The broken lines showing the phone forms no part of the claimed design.
